UNITED STATES PATENT OFFICE.

NATHAN L. GLAUBER AND ABERAHAM SCHLANK, OF NEW YORK, N. Y.

DESIGN FOR A VASE.

Specification forming part of Design No. 5,918, dated June 11, 1872.

Specification describing a Design for a Vase, invented by NATHAN L. GLAUBER and ABERAHAM SCHLANK, both of the city, county, and State of New York.

The nature of our design is fully represented in the accompanying drawing, to which reference is made—A indicating the base, B the body, and C the neck of the vase. The neck of the vase is formed of segments of circles, and a right line so as to form a cornice, D, while the body and base of the vase are united by a half-round bead, E. The vase is further ornamented with an archer surrounded by a

series of arrow-heads, F, forming an oval, G; but we will not claim the archer, as we may substitute other figures within the oval for the archer.

What we claim as our invention is—

A design for a vase, the contour and ornamentation being substantially as shown and described.

NATHAN L. GLAUBER.
ABERAHAM SCHLANK.
